UNITED STATES PATENT OFFICE

GEORGE E. NERNEY, OF ATTLEBORO, MASSACHUSETTS, ASSIGNOR TO BAY STATE OPTICAL COMPANY, OF ATTLEBORO, MASSACHUSETTS, A CORPORATION OF MAINE

DESIGN FOR AN OPHTHALMIC MOUNTING

Application filed October 10, 1930. Serial No. 37,211. Term of patent 14 years.

To all whom it may concern:

Be it known that I, GEORGE E. NERNEY, a citizen of the United States, and a resident of Attleboro, in the county of Bristol, State of Massachusetts, have invented a new, original, and ornamental Design for an Ophthalmic Mounting, of which the following is a specification, reference being had to the accompanying drawings, forming a part hereof.

In the drawings, in which therefor,

Figure 1 is a front elevation of an ophthalmic mounting showing my new design,

Figure 2 is a plan view of this mounting without the temple bars, and

Figure 3 is a perspective view of this mounting.

The rims of the mounting are made of a suitable non-metallic material such as zylonite, while the temple bars, the associated connecting members and the bridge, connecting the eyeglass rims, are of metal.

I claim:

The ornamental design for an ophthalmic mounting substantially as shown and described.

In witness whereof, I have signed my name to this specification, this 19th day of October, 1930.

GEORGE E. NERNEY.
